UNITED STATES PATENT OFFICE.

ERIC T. FRANZEN, OF MAPLEWOOD, NEW JERSEY.

SPARK PLUG.

Application filed March 5, 1923. Serial No. 622,768.

To all whom it may concern:

Be it known that I, ERIC T. FRANZEN, a citizen of the United States of America, residing at Maplewood, in the county of Essex and State of New Jersey, have invented new and useful Improvements in Spark Plugs, of which the following is a specification.

This invention relates to improvements in spark plugs as used in connection with internal combustion engines and has as one of its objects to provide a spark plug having a spark gap automatically controlled by the heat engendered by explosion of the gases within the engine cylinder.

Another purpose is to produce a spark plug in which the gap is closed initially due to the relative cold condition of the parts and which, becoming heated during operation, causes the gap to open variably according to the temperature of the plug and its associated elements.

A further aim is the provision of a spark plug so designed as to enable the user to ascertain whether or not the cylinder in which the plug is used is properly firing, by observation of the variable spark gap, thereby providing a visual means for detecting missing cylinders of internal combustion engines.

These several objects are attained by certain structural arrangements in the outer portion of the plug body and construction of parts therein, as hereinafter described and illustrated in the annexed drawing, forming part hereof, and in which:—

Figure 1 is a side view of a conventional type of spark plug, its upper portion being in section to show the application of an embodiment of the invention.

Figure 2 is a transverse sectional view taken on line 2—2 of Fig. 1.

Figure 3 is a perspective view showing one form of thermostatic couple as used in the device and drawn to an enlarged scale.

Figure 4 is a fragmentary sectional view illustrating the application of a modified form of the same.

As will be readily recognized in the drawing a conventional spark plug is shown having a body 10 terminating in a reduced screw-threaded portion 11 and containing an insulator 12 held by the clamp nut 13.

A fixed electrode 14 extends below the threaded base 11 and contained centrally in the insulator is the mating electrode 15.

The upper portion of the insulator 12 contains a circular recess or chamber 16 open at its outer end which is internally screw threaded to receive a bushing 17 having an extending flange 18.

Disposed in the recess 16 is a relatively thin sleeve 19 made of non-conducting, transparent material, as mica, the same covering the inner ends of transverse openings 20 formed through the insulator.

Into this recess, concentric with the sleeve 19, extends the upper end of the electrode 15, terminating within the range of the sight openings 20.

Threaded into the bushing 17 is a metal plug 21 provided with a washer 22 resting on the flange 18 and above the washer a clamp nut 23 is threaded on the stud 21.

A thermostatic element, generally designated by the numeral 25 adapted to operate by changes in temperature, (best shown in detail in Fig. 3) is composed of two metallic plates, 24 and 26, having different ratios of expansion when subjected to heat, as steel and brass, is coiled at one end to produce a neck 27, the same being tight fitted into a hole eccentrically formed in the inner end of the plug 21.

These plates are permanently and fixedly united over their entire contacting surfaces and are so bent as to present the brass surface into position to make positive electric contact with the adjacent end of the electrode 15.

In the modification shown in Fig. 4 the bushing is formed with a bottom wall 17' and has an opening at one side through which the thermostatic couple is entered and bent at a right angle, the same being held rigid by the inner end of the stud 21, the device being in all other respects as previously described and operates in the same manner.

In starting a cold engine the sparking current will be conveyed from a conductor clamped between the nut 23 and washer 22, to the stud 21 and thence through the thermostatic couple 25 to the electrode 15 direct.

As the engine and its associated parts become heated, the inner or brass plate 26 elongates, causing the couple to curve away from the electrode, presenting an appreciable space therebetween, constituting a spark gap, tending to intensify the effect of the current, increasing the action of the delivered spark in a well known manner.

The spark passing the gap is readily observable through the openings 20 but entrance of dust, oil, gases and the like are prevented, due to the transparent sleeve 19 enclosing the recess in which the spark gap is confined, and it is to be noted that all the several parts are enclosed within the body of the spark plug, no unsightly projections or excrescencies being used.

10 Obviously when these plugs are in use in a multi-cylinder engine, the user may, by observing the distances between the couple 25 and the electrode 15 determine the conditions within the cylinders.

15 Owing to the high temperature attained by the succession of explosions within the cylinders, it will be understood that the gaps between the electrodes 15 and the couple 25 will, under proper conditions, remain at 20 their maximum, but should any cylinder miss firing for any appreciable length of time, the gap in its plug will materially shorten so that the user may determine almost instantaneously, the condition.

25 Although the foregoing is descriptive of the preferred embodiment of the invention, it will be apparent that minor changes may be made in its construction, without the exercise of invention or conflicting with the 30 scope of the claims hereto appended.

Having thus described my invention, what I claim as new and desire to secure by Letters Patent, is:—

1. A spark plug having an insulated electrode, a thermostatic couple forming part of said electrode, said couple being pendantly supported normally in contact with the electrode and in the circuit leading thereto, said couple being wholly enclosed 40 within the outer portion of the insulator and having its terminal visible through openings in the insulator.
2. A spark plug comprising a body having an electrode, an insulator secured in said body, said insulator having a recess in its upper portion, a second electrode carried by said insulator and projecting into the recess, a terminal plug fixed in the outer end

of said insulator, and a thermostatic couple carried by said plug adapted to directly convey current to said electrode within the recess or present a gap therebetween.

3. A spark plug comprising a body having a fixed electrode, an insulator carried by said body, said insulator having an open axial recess in its outer end, a second electrode extending into the mentioned recess, a bushing fixed in the outer end of the recess, a terminal plug in said bushing, and a thermal unit fixed in said plug extending into the recess adjacent said second electrode and adapted to convey current thereto, said unit being automatically movable to or from the electrode.

4. A spark plug comprising a body having a fixed electrode, an insulator carried by said body, said insulator having an open axial recess in its outer end and transverse openings intersecting the recess, a transparent sleeve fitting the recess, a terminal fixed on the end of said insulator over the recess, and a thermal unit attached eccentrically to said terminal adapted to convey current to said second electrode either by direct contact or through a gap therebetween in accordance with the temperature of said parts.

5. In a spark plug having an outwardly extending insulator, said insulator containing an axial chamber in its outer portion, an electrode having a part entering the chamber, said insulator having transverse openings intersecting the chamber in the plane of the electrode end, a transparent sleeve in said chamber covering the inner ends of the mentioned openings, a bushing threaded into the open end of the chamber, a terminal plug in said bushing and a thermal couple fixed in said plug and movable in the chamber to convey current to said electrode.

This specification signed and witnessed this 19th day of February, 1923.

ERIC T. FRANZEN.
